METHOD OF AND MEANS FOR MARKING
LUMP MATERIALSJohn A. Cormack, Milwaukee, Wis., assignor to
Dustlix Corporation, Milwaukee, Wis., a corporation of Wisconsin

Application December 4, 1937, Serial No. 178,049

14 Claims. (Cl. 216—33)

This invention relates to an improved method and means for marking coal, crushed stone or like lump materials for the purpose of identifying it.

A simple and effective method of marking such materials is disclosed in my prior application, Serial No. 132,341, filed March 22, 1937. In the method shown in that application, a distinctive strip of paper or the like is adhesively applied to a mass of coal or the like, the strip adhering to some of the lumps and being torn into fragments by subsequent movement of the lumps within the mass. When the lumps bearing the distinctive fragments become mixed throughout the mass, the distinctive medium serves to identify the entire mass, as well as subsequently segregated portions of the mass.

One object of the present invention is to provide an improved method of applying and distributing fragments of a distinctive medium to and throughout a mass of lump material in a manner to identify the mass and subsequently segregate portions of the mass.

Another object is to provide a machine for effectively and efficiently carrying out my novel method.

Another object is to provide an improved machine for feeding and separating sheet material into fragments.

Other objects and advantages will appear, expressed or implied, from the following description of a novel method which I have employed in practicing the present invention.

In the accompanying drawing:

Figure 1 is a vertical sectional view taken along the line 1—1 of Fig. 2, of a simple machine for carrying out the method of the present invention, with a schematic showing of the identifying medium being applied to lumps of coal, in accordance with the method of the present invention.

Fig. 2 is a top plan view, on a larger scale, of the mechanism illustrated in Fig. 1.

Fig. 3 is a vertical sectional view taken substantially along the line 3—3 of Fig. 1 illustrating the strip feed mechanism.

Fig. 4 is a view in end elevation showing the strip tearing mechanism.

As in the application mentioned above, identification of the mass of coal or like lump material is effected in this instance by the use of a distinctive medium, preferably of paper or like material in strip form, fragments of which are adhesively affixed to lumps of the material and mixed throughout the mass. In the accompany-

ing drawing, such a distinctive strip is shown at A entering the machine from an appropriate source. The strip A is rendered distinctive by printing, coloring or otherwise marking the same. The strip is preferably perforated, scored, or otherwise treated to render it easily separable by tearing into fragments or individual labels B. The strip shown is perforated, at intervals C, each line of perforations terminating in slits D which facilitate tearing of the strip along the lines of perforations.

As the strip A is fed into the machine over an appropriate guide or chute 9, an adhesive is applied thereto in any conventional manner, depending upon the characteristics of the adhesive used. In this instance an appropriate adhesive applying tube or nozzle is shown at 10, supplied from an appropriate source, and arranged to apply a ribbon-like coating of adhesive E along the center of the strip, and leaving margins F of the strip uncoated so as to avoid interference with the feed and tearing rollers, later to be described.

The strip A is preferably continuously advanced along the guide 9 and beneath the adhesive applying tube 10 by sets of upper and lower feed rollers 11 and 12 which grip between them the ungummed margins of the strip. The upper rollers 11, preferably spaced apart to avoid the intermediate adhesive coating, are fixed to a shaft 13, driven by appropriate means, such as a pulley and belt 14. The lower coating rollers 12, respectively opposed to the rollers 11, are fixed to a lower shaft 15.

The machine shown also includes a strip tearing and fragment ejecting mechanism preferably comprising a single pair of opposed upper and lower rollers 16 and 17 disposed to receive the strip from the feed rollers 11 and 12 and to grip one ungummed margin of the strip. Rollers 16 and 17 are respectively fixed to and driven by upper and lower shafts 18 and 19 at a peripheral speed higher than that of the feed rollers 11 and 12, so as to tension that section of the strip disposed between them and the feed rollers and thereby effect intermittent tearing of the strip along the lines of perforations C. It will be noted that by arranging the rollers 16 and 17 to grip only one margin of the strip the resulting tension is concentrated along an edge of the strip where it is most effective to produce tearing. It will also be noted that the guide 9 extends between the feed and tearing rollers in a manner to support the torn end of the strip and to assure entry thereof between the tearing rollers.

The tearing rollers 16 and 17 may be driven in

various ways, but in this instance they are shown driven from the feed rollers 11 and 12 in a simple and effective manner. For this purpose a gear 20, fixed to the upper feed roll shaft 13 adjacent one end thereof, meshes with a smaller gear 21 on the lower tearing roll shaft 19, and a similar gear 22 fixed to the other end of the lower feed roll shaft 15 meshes with a smaller gear 23 fixed to the upper tearing roll shaft 18. In this way the lower tearing roll 17 is driven in the same direction as the lower feed rollers 12 but at higher speed, and the upper tearing roll 16 is driven in the same direction as the upper feed rollers 11 but at a higher speed.

15 The machine shown is designed for mounting adjacent a moving mass of coal or other lump material preferably passing therebeneath, as down the breaker chute of a mine, or a loading chute, or the like. In Fig. 1 of the drawing, 20 this is schematically suggested, lumps of coal G being shown moving down a chute and onto a conveyor H which carries them past the machine. As the adhesive labels B are ejected by the tearing rollers 16 and 17, they are cast upon 25 the mass of coal moving therebeneath, and become adhesively attached to some of the lumps of the mass. During further movement and subsequent handling of the lump material, the lumps bearing the labels will become mixed throughout 30 the mass, and thereby serve to identify the mass as well as subsequently segregated portions thereof.

It is not contemplated that every fragment of the identifying strip will remain attached 35 to a lump of coal, nor that the fragments will adhere securely to the lumps throughout their entire length; it is sufficient, however, that some of the fragments of the paper adhere to the coal lumps to the extent that the identifying fragments will be carried by the lumps throughout 40 subsequent handling. Nor is it contemplated that every lump of coal will carry a fragment of the strip; if in any given amount of coal there are a certain proportion of lumps carrying the 45 identifying fragments, it will be sufficient to identify the mass.

Various changes may be made in the embodiment of the present invention hereinabove specifically described without departing from or sacrificing the advantages of the invention as defined in the appended claims.

I claim:

1. The method of marking a mass of lump material which consists in separating a distinctive 55 medium into adhesive bearing fragments, delivering said fragments to the mass and into adhesive contact with lumps in the mass, and distributing said fragments throughout the mass by relative displacement of fragment-bearing lumps 60 within the mass.

2. The method of marking a mass of lump material which consists in preparing adhesive-bearing fragments of a distinctive medium, and casting said fragments into adhesive contact with 65 lumps contained in the mass, and distributing said fragments throughout the mass by relative displacement of fragment-bearing lumps within the mass.

3. The method of marking a mass of lump material which consists in separating an adhesive-bearing distinctive strip into successive adhesive-bearing fragments, and casting said fragments successively into adhesive contact with 70 lumps contained in the mass.

4. The method of marking a mass of lump

material which consists in preparing adhesive-bearing fragments of a distinctive strip, and casting said fragments onto lumps contained in the mass into adhesive attachment therewith.

5. The method of marking a mass of lump material which consists in separating an adhesive-bearing distinctive strip into successive fragments, and adhesively attaching said fragments to lumps contained in the mass by casting said fragments onto the mass. 5

6. The method of marking a mass of lump material which consists in rendering a distinctive strip adhesive, separating said strip into successive fragments, and casting said fragments into adhesive contact with lumps contained in the mass. 10

7. The method of marking a mass of lump material which consists in rendering a distinctive strip adhesive, advancing said strip to a point adjacent the mass, and separating and casting portions of said strip onto the mass thereby to effect adherence between said portions and lumps contained in the mass. 20

8. An apparatus for marking a mass of lump material comprising means for rendering a distinctive strip adhesive, and means for separating and casting portions of said strip into adhesive contact with lumps contained in the mass. 25

9. An apparatus of the character described comprising means for rendering a distinctive strip adhesive, means for receiving and feeding said adhesive strip, and means coacting with said feeding means to intermittently tension and tear the adhesive strip, said last named means being disposed to receive the strip and to eject portions 30 torn therefrom. 35

10. An apparatus of the character described comprising means for rendering a distinctive strip adhesive along a central portion thereof, a set of rollers for feeding the strip, and a set of rollers driven at a higher peripheral speed than said feed rollers and coacting therewith to intermittently tension and tear the strip, all of said rollers contacting said strip at portions unaffected by said adhesive. 40

11. An apparatus of the character described comprising a set of rollers for feeding a strip, said set of rollers comprising upper and lower feed rollers gripping said strip at both edges thereof, and a set of rollers comprising upper and lower rollers gripping said strip along one edge only thereof, said last named rollers coacting with said first named rollers to tension one edge of the strip and thereby intermittently tear the latter. 50

12. An apparatus of the character described comprising a pair of rollers coacting to feed a strip, a second pair of coacting rollers disposed to receive and grip the strip, a gear rotatable with each of said first named rollers, and a gear rotatable with each of said last named rollers and engaged with one of said first named gears for effecting rotation of said last named rollers at a peripheral speed higher than said first named rollers to thereby tension and intermittently tear the strip. 60

13. In a device of the character described, the combination of upper and lower feed rollers gripping a strip and rotatable to feed the same, 70 a large gear rotatable with each of said rollers, upper and lower tearing rollers receiving said strip from said feed rollers and gripping the same, a small gear rotatable with each of said tearing rollers, the upper of said small gears being en- 75

gaged with the lower of said large gears, and the lower of said small gears being engaged with the upper of said large gears to thereby induce rotation of said tearing rollers in the same direction as said feed rollers and at a higher peripheral speed to thereby tension and intermittently tear said strip.

5 14. In an apparatus of the character described, the combination of upper and lower feed rollers 10 gripping a strip along one edge thereof, upper and

lower feed rollers aligned with and rotatable with said first named rollers and gripping said strip along the opposite edge thereof, and upper and lower tearing rollers receiving said strip from said first named rollers and gripping said strip along one edge only thereof, said last named rollers having a peripheral speed higher than said first named rollers to thereby tension and intermittently tear said strip.

JOHN A. CORMACK. 10
